UNITED STATES PATENT OFFICE.

CLAUDE L. FRIEL, OF CHICAGO, ILLINOIS.

PRINTING-PRESS.

1,347,627.

Specification of Letters Patent. Patented July 27, 1920.

Application filed September 22, 1919. Serial No. 325,478.

To all whom it may concern:

Be it known that I, CLAUDE L. FRIEL, a citizen of the United States, residing at the city of Chicago, county of Cook, State of Illinois, have invented new and useful Improvements in Printing-Presses, of which the following is a specification.

My invention relates to a press for printing and numbering blank bank checks.

10 In the methods now in common use a form is set up which contains the matter for each of the number of checks that are to be contained on a page. The sheets for the pages are then printed and afterward numbered. 15 This necessitates setting up the same subject matter as many times as there are checks on a page, and then subsequently numbering the checks which requires the handling of the sheets a second time.

20 It is the object of my invention to set up the matter for a check only once, and successively print such matter as many times on a sheet as there are to be blank checks on a page, and at the same time to successively 25 number the same.

In the drawings forming a part of this application, Figure 1 is a side elevation of a machine designed to print 3 checks to the sheet, Fig. 2, is a top plan of Fig. 1; Fig. 3, 30 is a front end view; Fig. 4 is a vertical cross section on the line α^4 of Fig. 1; Fig. 5 is a vertical cross section on the line α^5 of Fig. 1; Fig. 6 is a vertical section of a portion of the mechanism on the line α^6 of Fig. 1; Fig. 35 7 is a detail of the check carriage and its operating mechanism; Fig. 8 is a detail of the regulating mechanism of certain parts of the printing mechanism; Figs. 9, 10, and 11, are enlarged details.

40 Referring to the drawings 15 are the floor members of the frame to which are secured the side members 16 that are connected by suitable transverse members 17. Secured to and resting upon the top of the frame is the 45 inclined table or board 18, upon which the sheets 19 that are to be printed into blank checks are deposited. At the lower end of this table are the positioning fingers 20, which are secured to shaft 21, mounted in 50 bearings 22, secured to and part of the side members of the frame. In front of fingers 21 are the grippers which consist of the lower finger members 23 and the upper finger members 24 which last fingers are 55 secured to shaft 25 mounted in bearings 26 secured to carriage 27. In the operation of

the machine the carriage travels back and forth from the head to the tail, and from the tail to the head. The operator slides the top sheet of paper off the pile, down the 60 table and into contact with fingers 20. At this time the carriage is approaching the head, and arm 28 which is secured to shaft 25 is brought beneath plate 29, which plate is mounted on and carried by rod 30, slidably mounted in bearings secured to the side members of the frame. To the lower end of rod 30 is secured a bell crank lever 31 pivoted at 32 to the frame. The other end of lever 31 is connected to operating bar 70 33, which carries a small roller 34 at its forward end, which roller enters a cam groove 35 in wheel 36, mounted on shaft 38. The rotation of wheel 36 through connecting mechanism causes plate 29 to depress the 75 free end of arm 28, and thereby rock shaft 25, and cause the free ends of fingers 24 to be raised and they remain in their raised position until carriage 27 reaches its forward limit of travel, at which time member 23 is 80 below and member 24 is above the edge of the sheet that is to be printed. Plate 29 is then returned to its inoperative position as shown in Fig. 1, and the grippers engage and hold the paper. Shaft 21 has an arm 85 41 which is connected by link 42, with a rock bar 43, pivoted at 44, to the frame. To the other end of bar 43 is connected an operating bar 45 which carries a small roller 46 at its lower end, which roller enters a cam 90 groove 47 in wheel 36. At the same time that the grippers close on the sheet of paper the free ends of the positioning fingers through the mechanism last described are raised and held out of the way of the sheet 95 of paper. At the time carriage 27 reaches its forward limit of travel it engages a bumper roller 48 carried by arms 49 and 50. Roller 48 at this time enters into a notch 51 (see Fig. 7) in a ledge 52 carried by the sides of 100 carriage 27.

The carriage now commences its travel toward the rear of the machine and roller 48 moves up and out of notch 51 and travels down into notch 53, thereby stopping the 105 travel of the carriage. The travel of the carriage to this point has brought the front end of the paper beneath the printing mechanism shown at 54, and the form descends and prints the first impression of the check 110 on the paper. The printing mechanism consists of a frame 55 which is carried by pit-

man rods 56 which are carried and moved by disks 57, which are mounted on shaft 57^a. Shaft 57^a has mounted thereon gear 57^b that meshes with idler gear 58. Gear 58 meshes with gear 59 on shaft 60. Mounted on shaft 60 is gear 60^a that meshes with gear 61 on shaft 38. Frame 55 carries a printing form 62 which when the head descends engages the paper and prints the 10 blank check. Frame 55 also carries a numbering device which at the same time prints the number of the check. 62^a are the inking rollers which ink the form in the well known manner. As soon as check No. 1 is printed 15 roller 48 is moved up out of notch 51 and the carriage moves toward the rear. As will be seen from Fig. 7 a rod 63 is connected to arm 50 and to lever 64 which is pivoted at 65 to the frame. The other end of lever 64 20 carries a roller 66 which is engaged by cam wheel 69 on shaft 38. This wheel is shown in dotted lines in Fig. 7 and has three short teeth 70 and one long tooth 71. When these teeth engage roller 66 by means of connecting mechanism roller 48 is raised. The short 25 teeth provide for the momentary raising of the roller which occurs while the carriage is traveling to the rear, and the long tooth holds roller 48 elevated while the carriage 30 is traveling to the head.

The carriage is caused to travel by means of the following mechanism. A lever 72 is pivoted at 73 to the frame, and carries on its side a roller 74 which enters cam groove 35 75 in wheel 76 mounted on shaft 38, best shown in Figs. 4 and 7. The upper end of lever 72 is pivotally connected by link 77 to rack bar 77^a. Rack bar 77^a meshes with pinion 83 on shaft 84. Mounted on 40 shaft 84 are gears 85 which mesh with teeth 27^a on the sides of the frame of the carriage.

At certain places groove 75 is enlarged as 45 shown in Fig. 7 so that at these points the roller will not hold the carriage rigid but will permit roller 48 to properly position the carriage so that the form will print at the right place on the sheet. The form of groove 75 is such that carriage 27 is reciprocated. When carriage 27 has nearly reached the limit of its travel toward the rear and after the last check on the sheet is printed 50 arm 28 passes beneath plate 78 which is carried by rod 79 (see Fig. 1) mounted to slide 55 vertically in bearings 80 secured to the frame. At this time plate 78 descends thereby rocking shaft 25, which causes the elevation of the free ends of fingers 24 and the sheet of printed checks is released and falls 60 upon the inclined receiving table 81. The descent of plate 78 is caused by bell crank lever 82 pivotally mounted at 83^a to the frame which is connected to rod 79 and to bar 33 which bar is reciprocated as before 65 explained.

As before explained the paper on which the checks are printed is carried by the grippers as it travels to the rear and is supported by a bed plate which extends to the rear of the printing mechanism and terminates at 70 table 87 which is pivotally mounted at 88 to the frame. The final travel brings the printed sheet over this table and when the grippers are released as before explained the free end of the table is caused to descend and 75 the sheet is deposited in a box. This movement is effected by bell crank lever 89 which is pivoted at 90 to the frame and has one end connected to bar 33 and the other to bar 91 which is connected to table 87. Mounted on 80 shaft 38 is a mutilated gear 92, which engages pinion 60^a on shaft 60. A portion of the teeth of gear 92 are entirely cut away as shown in Figs. 7 and 8 at 93 and another portion is only partially cut away as shown 85 at 94 in Fig. 8. With pinion 60^a in the position shown in Figs. 7 and 8 three checks will be printed to the page. If pinion 60^a is shifted to the position shown in dotted lines only two checks will be printed to the page. 90

In case it is desired to print checks of different widths, ledge 52 is provided with adjustable sections 52^a as shown in Fig. 9 whereby the travel of the carriage is adjusted to stop at the desired width of the 95 check.

These sections have thumb screws 52^b which are movable in slots in the base 52^c of the ledge and clamp the sections in their adjusted positions. 100

An ink fountain 105 having rollers 106 and 107 supplies ink to rollers 62^a. Roller 107 has a sprocket wheel 108 which is connected by chain 109 to a sprocket wheel on shaft 38, whereby the rollers are operated in 105 the usual manner.

Mounted on shaft 60 is a mutilated wheel 95 which has a notch 96 in which a lock roller 97 is received to lock gears 60^a in position so that the teeth of the mutilated gear 110 92 may properly engage with gear 60^a. Lock roller 97 is carried in plunger 98 which is mounted in bearing 99 and is moved upwardly into notch 96 by spring 100 when said notch registers with said roller 97. 115

On shaft 101 is mounted pinion 102 which meshes with gear 61 on shaft 38. Shaft 101 carries a pulley 103 to which power is applied by belt 104.

Having described my invention I claim: 120

1. A printing press comprising a frame, a carriage mounted in said frame, means on said carriage to grip and carry a sheet of paper; means to intermittently move said carriage; in combination with printing 125 means adapted to print upon the paper carried by said carriage when said carriage stops in its travel toward the tail.

2. A printing press comprising a frame; a carriage mounted in said frame and adapt- 130

ed to travel back and forth from head to tail and from tail to head; means to cause an intermittent travel of said carriage from head to tail and a continuous travel of said carriage from tail to head; means on said carriage to grip and carry a sheet of paper from head to tail; means to release said paper when the carriage reaches its limit of travel toward the tail; in combination with printing means adapted to print upon the paper on said carriage as it stops on its travel toward the tail.

3. In a printing press a frame; a carriage mounted thereon to travel from head to tail and from tail to head; means to cause an intermittent movement of said carriage as it travels toward the tail and a continuous movement as it travels toward the head; means to release said paper when the carriage reaches the tail, a printing mechanism mounted on said frame; and means to operate said printing mechanism to cause it to print upon the paper on the carriage when the carriage stops in its travel toward the tail.

4. In a printing press a frame; a carriage mounted therein to travel from head to tail and from tail to head; a lever operatively connected to said carriage at one end and pivotally connected at the other end to said frame; a cam wheel mounted in said frame, said wheel having an irregular shaped cam groove in its side; a roller mounted on said lever and entering into said cam groove; whereby when said wheel is rotated said frame is caused to travel from head to tail and back and make periods of stops in its travel from head to tail.

5. In a printing press a frame; a carriage mounted therein to travel from head to tail

and back; grippers mounted on said frame; means to open said grippers at the ends of the travel of said frame; a lever operatively connected to said carriage at one end and pivotally connected at the other end to said frame; a cam wheel mounted in said frame, said wheel having an irregular shaped cam groove in its side; a roller mounted on said lever and entering into said cam groove, whereby when said wheel is rotated said frame is caused to travel from head to tail and back and make periods of stops in its travel from head to tail; printing mechanism mounted on said frame; and means to operate said printing mechanism in the periods of the stop in the travel of said frame from head to tail.

6. In a printing press, a carriage mounted therein to travel from head to tail and back; grippers mounted on said carriage; means to open said grippers at the ends of travel of said carriage; a lever operatively connected to said carriage at one end and to the press frame at the other end; a cam wheel mounted in the press frame, said wheel having an irregular groove in its side, said groove being enlarged at different points; a roller mounted on said lever adapted to travel in said groove, whereby when said wheel is rotated said carriage is caused to travel from head to tail and back and make periods of stops in its travel toward the tail; and gages adjustably mounted upon said carriage, whereby the position of the carriage at the periods of stop can be changed as desired.

In witness that I claim the foregoing I have hereunto subscribed my name this 6th day of September, 1919.

CLAUDE L. FRIEL.
